ROBERT BINNIE, OF BOLIVAR, PENNSYLVANIA.

SELF-CLEANING DRILL.

1,081,655.

Specification of Letters Patent. Patented Dec. 16, 1913.

Application filed January 27, 1913. Serial No. 744,463.

To all whom it may concern:

Be it known that I, ROBERT BINNIE, a resident of Bolivar, in the county of Westmoreland and State of Pennsylvania, have invented a new and useful Improvement in Self-Cleaning Drills, of which the following is a specification.

This invention relates to a self-cleaning rock drill.

10 The object of the invention is to provide an improved rock drill so arranged that a continuous supply of water or other liquid may be conducted to and away from the cutting edges of the drill bit to carry away the mud, dirt and chips formed thereby, thereby increasing the capacity and effectiveness of the drill and decreasing the time of the drilling operation.

20 The invention comprises the construction and arrangement of parts hereinafter described and claimed.

In the drawings Figure 1 represents a sectional elevation of drilling apparatus embodying one form of the invention; Fig. 2 is a horizontal section of the same on the line 2-2, Fig. 1; and Fig. 3 is a sectional elevation illustrating a modification.

The drilling apparatus shown in the drawings comprises a tubular drill rod 1, which is hollow to provide a longitudinal passage 2 therein, and preferably is formed in one or a plurality of sections detachably secured to each other, as at 3, to suit the depth of the hole being drilled. At its lower 30 end the drill rod is internally threaded, as at 4, to receive the threaded reduced end or tang 5 of a drill bit 6. The drill bit may be of any desired type and is provided with a point having the usual cutting edges 7, and 35 is preferably also provided with a fluted shank, as shown in Fig. 3, having one or more channels 8 therein. The drill bit 6 is provided with a longitudinal bore 9, which at one end communicates with the passage 2 in the drill rod 1, and which may extend for the full length of the drill bit, but preferably for only a short distance at its upper 45 end. As shown, passage 9 communicates with one or more lateral ports or passages 50 10 which lead outwardly to the channels 8.

The drill bit 6 is surrounded by a tubular shield 11, the lower end of which is slightly flared, as at 12, and extends down fairly close to the cutting edges 7. This shield has a loose fit on the shank 6 and at its upper 55 end extends above the lateral ports or pas-

sages 10. It is rigidly held in adjusted position by any suitable means, such as a set screw 13 therein which bears at its inner end against the shank 6 or drill rod 1, but preferably by a collar 14 loosely slidable on the outside of the drill rod and secured thereto in adjusted position by a set screw 15.

Within the passage 2 in the drill rod 1 is located a suitable non-return check valve of any preferred type. This may be arranged to seat in either direction, that is, either upwardly or downwardly. In the form shown in Fig. 1, the drill rod tube 1 is provided with a transverse wall having a port 16 therein, and surrounded by a valve seat 17, against which seats a ball-valve member 18. Said ball is held in the tube by any suitable means, such as the cross pin 19 and, if desired, may be normally held yieldingly to its seat by a light spring 20, although this is not essential and may be omitted. In the form shown in Fig. 3, the ball valve 18a seats downwardly by gravity alone and no spring is necessary.

Any suitable means may be provided for reciprocating the drill, such as a motor, driven by steam, electricity, or compressed air, or the drill rod may be reciprocated by hand. In Fig. 1 the drill rod is shown as suspended from a rope or cable 21, which at one end is attached to a movable member, such as a walking beam (not shown), and at its other end is secured to an eye member 22 having a shank threaded into the internally threaded end of the drill rod 1. The upper end of the drill rod is provided with one or more lateral ports 23, communicating with the passage 2, and through which the liquid is supplied to the drill. As illustrated in Fig. 1, the liquid is admitted to the hollow drill rod from a supply tank or vessel 24, shown as a sleeve or jacket, and which is of such size and so arranged as to hold a sufficient quantity of liquid for the drilling operation. The upper portion of the vessel is flared outwardly, as at 25, so that it can be easily filled with liquid, and the outwardly flared portion rests upon one or more supports 26 around the hole. These 101 may be either integral with the vessel 24 or merely separate blocks placed under the outwardly flared portion 25. The main body portion of the vessel 24 is in the form of a tube or cylinder 27, which internally is of 110 larger diameter than the external diameter of the drill rod, and externally is of smaller

diameter than the hole. At its extreme lower end tube 24 is bent or turned inwardly to form an internal flange 28. The rod may be slidable in the sleeve, in which case a stuffing-box or other suitable means may be provided at the lower end of the sleeve for securing a liquid-tight seal between the sleeve and rod. If desired, however, the sleeve or jacket may be rigidly secured to the rod to move therewith, as by welding the flange 28 to the rod at the proper location, such arrangement being particularly desirable for hand-operated churn drills.

The apparatus described is used in the following manner: The parts are assembled in the relations shown in Fig. 1 and a supply of liquid, such as water, is introduced into the sleeve or jacket 24 through the open upper end thereof. The drill rod is then reciprocated to cause the cutting edges 7 to impinge on the bottom of the hole and deepen the same. Liquid flows from the vessel 24 through the ports 23 and into the space or passage 2 within the drill rod and thence downwardly to the check valve. At each upward movement of the drill rod the pressure of the water is sufficient to slightly open the check valve and permit a quantity of water to flow therethrough, the check valve automatically closing as the drill rod begins to move downwardly. The water which passes the check valve flows through passage 9 and lateral ports 10 in the shank of the drill bit and then downwardly along the channels 8 in the fluted shank thereof and within the shield 11 until it reaches the cutting edges of the drill. A continuous supply of fresh water is consequently delivered to the cutting edges of the drill during the drilling operation. The water then flows upwardly away from the cutting edges of the drill along the outside of the shield 11 and sleeve 24 and out at the top of the hole, carrying with it the mud, dirt, and chips formed by the drilling operation. In this manner all the energy of the drill is expended in the cutting operation, thus permitting an extended drilling operation to be carried on without pulling the drill rod out of the hole and cleaning the latter in the ordinary manner. If desired, and especially when the hole is of some depth, the drilling operation can be carried on for a period of time and the drill rod and drill then removed and the hole cleaned out. Under such circumstances the continuous supply of fresh water to the cutting edges of the drill very quickly frees the bottom of the hole of mud and dirt and secures greater efficiency of the drill. The drilling operation can also be carried on for a long time without cleaning out the hole. It will of course be understood that as the drilling operation progresses additional segments or sections are added to the drill rod

1. The tube 24 may of course be made of any length desired, but preferably is of greater length than the several sections of the drill rod so that a new section thereof can be added before ports 23 pass beyond the lower end of the sleeve as the drill sinks into the hole. 70

For drilling in hard rock I prefer to use the arrangement shown in Fig. 3, which in some respects is a reversal in operation of the form shown in Fig. 1. The upper end of the drill rod 1 shown in Fig. 3 is threaded to receive the threaded nozzle 30 of a fitting 31. The latter is provided with a shank or tang 32 which is adapted to be secured to the operating motor, or to which the suspending rope or cable may be attached. Fitting 31 is provided with a longitudinal passage 33 communicating with the passage 2 in drill rod 1, and with a transverse passage 34 open to the atmosphere at both ends through tubular extensions 35. This form of device is also provided with a shield 11, as in the form shown in Fig. 1, and as above stated, the ball valve 18^a seats downwardly 90 instead of upwardly. With this form of device the supply of water is introduced directly into the hole being bored and flows down around the outside of the drill to the cutting edges of the bit. At each downward movement of the drill the pressure of the water upwardly against the check valve 18^a unseats the latter and permits water and mud to flow upwardly along the channels 8 in the drill and inside of the shield 11, 100 thence through ports 10 and passage 9 and past the check valve 18^a. It then flows through the passage 2 in the drill rod and is discharged from the ends of the tubular extensions 35 into a suitable pan or vessel 36. When the drill is operated by hand the extensions 35 can be used as handles. 105

The apparatus described is simple and can be readily manufactured and greatly increases the capacity of the ordinary drill. It rapidly conducts the dirt, mud, and chips away from the drill point and thus decreases the retarding effect of the thick mud usually formed by the drill. 110

What I claim is:—

1. A rock drill, comprising a hollow shank, a hollow bit secured thereto and provided with a transverse passage therethrough, said bit having a longitudinally extending channel communicating at one end with said transverse passage, and a tubular shield surrounding said bit, whereby when the drill is reciprocated liquid will flow through said hollow shank and bit and along said channel between said shield and bit. 120

2. A rock drill, comprising a hollow drill rod, a drill bit secured thereto and provided with a passage communicating with the passage in said drill rod, a shield surrounding said drill bit, and a non-return check valve 130

in one of said passages arranged to permit the flow of liquid in one direction only through said passages and within said shield as the drill rod is reciprocated.

- 5 3. A rock drill, comprising a hollow drill rod, a drill bit secured to said drill rod, a tubular shield surrounding said drill bit, said drill being fluted to provide a longitudinal channel and having a passage communicating at one end with said channel and at the other end with the passage in said drill rod, and a non-return check valve in one of said passages arranged to permit the flow of liquid in one direction only therethrough.
- 10 10. A rock drill, comprising a hollow drill rod, a drill bit secured thereto and provided with a passage therethrough communicating with the passage in said drill rod, a shield surrounding said drill bit, and a non-return check valve in one of said passages arranged to seat upwardly and to permit the flow of liquid downwardly through said passages and between the shield and drill bit to the cutting edges of the bit.
- 15 15. A rock drill, comprising a hollow drill rod, a drill bit secured thereto and provided with a passage therethrough arranged to conduct liquid to the drill point, a check valve in one of said passages arranged to seat upwardly, and a tube surrounding the upper portion of the drill rod and in which the same is slid able, said drill rod being arranged to permit the supply of liquid to the passage therein from the space within said tube.
- 20 20. A rock drill, comprising a hollow drill rod, a drill bit secured thereto and provided with a passage therethrough arranged to conduct liquid to the drill point, a check valve in one of said passages arranged to seat upwardly and to permit the flow of liquid downwardly through said passages and between the shield and drill bit to the cutting edges of the bit.
- 25 25. A rock drill, comprising a hollow drill

rod, a fluted drill bit secured thereto and provided with a passage therethrough for conducting liquid to the drill point, a shield surrounding said drill bit, and a jacket surrounding the upper portion of the drill rod 30 and arranged to supply liquid to the passage therein.

6. A rock drill, comprising a hollow drill rod, a drill bit secured thereto and provided with a passage therethrough arranged 35 to conduct liquid to the drill point, a check valve in one of said passages arranged to seat upwardly, and a tube surrounding the upper portion of the drill rod and in which the same is slid able, said drill rod being ar- 40 ranged to permit the supply of liquid to the passage therein from the space within said tube.

In testimony whereof, I have hereunto set my hand.

ROBERT BINNIE.
